UNITED STATES PATENT OFFICE

REUBEN E. OTTENHEIMER, OF BALTIMORE, MARYLAND

REFRIGERATOR

Application filed January 31, 1925, Serial No. 6,150. Renewed May 2, 1930.

This invention relates to refrigerators and particularly to a shelf intended primarily, but not exclusively for use in refrigerated display cases having a definite path of air circulation which it is desirable so to direct that it flows in a circuit over and across the shelf.

The purpose in so directing the circulation is two-fold. It keeps the cold circulating air from flowing directly in contact with the walls of the refrigerator, and particularly in contact with the glass panels of show-cases when these are near to and above the shelf. It thus reduces condensation on the outside of these walls or panels. Condensation is likely to occur wherever the walls of a refrigerator are maintained at a temperature below the dew point of the air in the room in which the refrigerator is used and in show-cases this defeats the display function of the case.

Furthermore, by confining the circulation to the portion of the case adjacent the shelf, the loss of refrigerative effect incident to the frequent opening of the service doors, when these are near the top, is minimized. In a well designed case it is possible to remove the doors altogether during rush periods with only slight increase of temperature in the lower portion of the case, and in fact some cases are used with an elevated service opening and no doors whatsoever. In all such cases my shelf is particularly useful.

The preferred embodiments of the invention are illustrated in the accompanying drawings, in which

Fig. 1 is a fragmentary plan view of a shelf embodying the invention;

Fig. 2 is an enlarged fragmentary section on the line 2—2 of Fig. 1;

Fig. 3 is a fragmentary section on the line 3—3 of Fig. 2;

Fig. 4 is a fragmentary section, similar to Fig. 2, showing a slightly modified form of shelf;

Fig. 5 is a vertical transverse section through a typical display case showing my improved shelf in place and intended to illustrate its utility.

The shelf is indicated generally by the

numeral 6 and is formed of a single piece of heavy sheet metal which may be galvanized or enameled to render its surface non-corrosive. It is ordinarily rectangular in form and is provided at its forward edge, i. e., 55 that edge which in use is near the glazed front of the case, with an upstanding, rearwardly inclined baffle or flange 7. This flange may be straight, as shown in Fig. 2, or may be rearwardly curved, as shown in 60 Fig. 4, or may be otherwise formed.

The shelf is preferably, but not in all cases necessarily, stiffened by a series of pressed ribs 8 which are formed by pressing it in dies, and these ribs are preferably 65 convex upward, as shown. Between these ribs the shelf is provided with a series of slots or elongated air ports 9 which, in the example chosen for illustration, are located adjacent the forward edge and hence partly 70 beneath the inclined baffle 7.

While I prefer to locate these air ports in the position shown in the drawings, other locations are possible and in certain types of case are preferable. In certain types of 75 case the air ports may be omitted altogether, as in Fig. 4, and the baffle be used alone. Furthermore, even where the air ports are quite close to the front of the case, as shown in Figs. 1, 2 and 3, they may be made of 80 any desired length and hence might extend for practically the entire length of the rib 8. The suggested variations being largely a matter of dimension, detailed illustration of all of them is considered unnecessary. 85

The purpose in forming the shelf with the baffles, ports and ribs, as described, can be explained more clearly in connection with a typical installation in a case in which the circulation passes through the shelf, such as that shown in Fig. 5. Here we have a case having a bottom portion 10 slightly higher at its rear than at its front. The vertical partition 11 is mounted in the bottom portion so that its lower edge is above the floor of the 90 case, and so that its upper edge is spaced from the top of the case to offer air ports through which air circulation may occur, as indicated by the arrows. Partition 11 is approximately two thirds of the distance from 95 100

- the front to the back of the case and shelf 6 spans the space from the partition 11 to the front of the case. Above shelf 6 is a glazed display case consisting of a frame structure 5 12 carrying a double glazed front transparent panel 13, glazed or other end panels 14, and overlapping glazed sliding doors 15 through which access is offered to the interior of the case.
- 10 For icing purposes a door or a series of doors 16 is provided and gives access directly through the top to the space at the rear of the partition 11. In use, block ice is placed in the space to the rear of the partition 11 or 15 a set of cooling coils may be there installed. When ice is used, crushed ice may, if desired, be placed forward of the block ice in the space beneath the shelf 6. If this last be done, the layer of crushed ice should be of 20 such depth that an air passage is left above it and beneath the shelf 6. The air circulates in the case illustrated rearward over the partition 11, then downward, then horizontally, beneath the shelf, and then upward through 25 the slots or ports 9 in the shelf 6, the air thus flowing in a closed circuit in the bottom portion of the case. The upstanding baffle or flange 7 performs the function of directing this air to the rear of the case as it rises 30 through the shelf, and particularly it prevents the air rising through the ports 9 from flowing into contact with the front glazed panel 13.
- In show-cases having other circulating 35 paths the baffle will perform a similar function. It should be noted that it is particularly effective in deflecting air which circulates beneath the supported articles by way of the grooves between the ribs 8.
- 40 The ribs 8 not only stiffen the shelf. They also support platters containing the displayed articles, or if such platters are not used, they support the displayed articles themselves in such a way that the air ports 45 9 can never be blinded. Even if the platter or the displayed article be laid directly over the ports 9, it will be so sustained above the main portion of the shelf 6 that air may flow up through the ports 9 and passing along the 50 channels between the ribs 8, may flow around the displayed article, and continue the normal circulation. The maintenance of circulation both over and under the refrigerated articles is highly desirable because in this 55 way the best refrigerative effect is secured.
- In cases of ordinary construction a number of shelf sections 6 arranged edge to edge are used, so that it is possible to remove the shelves for cleaning through the service openings and without removing the doors, if doors be used. The construction of the baffle 7 integrally with the shelf 6 offers a convenient and inexpensive construction, and one susceptible of ready cleaning. Since the baffle is 65 carried by and hence removable with the

shelf, it may be cleaned at the same time, and when it has been removed that portion of the case forward of such baffle is accessible for easy cleaning.

The shelf is thus strong, light, inexpensive 70 to construct, easily cleaned, and improves the action of refrigerators and particularly refrigerated display cases in a decided degree. As suggested, variations from the exact structure illustrated may be made, and I do not 75 limit myself except to the extent defined in the following claims.

What is claimed is:

1. A shelf for supporting articles to be refrigerated by currents of air, said shelf being 80 formed with alternating ribs and channels on its upper surface and having air ports extending through said shelf and opening into said channels; and a baffle mounted upon one edge of said shelf, overhanging a portion of 85 said ports and serving to deflect air rising through said ports across said shelf.

2. A refrigerator shelf for supporting articles to be refrigerated by currents of air, said shelf being formed with a ribbed top 90 surface, the ribs extending substantially to an edge of the shelf and an upwardly extending baffle mounted on said edge and overhanging a portion of the shelf, and serving to deflect air rising past said shelfing 95 across the same.

3. In a display refrigerator, a food chamber having a display panel and a shelf, means to effect a circulation of cooling air in said chamber whereby to refrigerate articles supported on the shelf, means to deflect said air away from said panel; said shelf being 100 formed with alternating ribs and channels on its upper surface and having ports extending through the shelf and opening into said channels for passage of cooling air through the shelf and between the shelf and articles supported thereby.

4. In a display refrigerator, a food chamber having a display panel and a shelf, means 110 to effect a circulation of cooling air in said chamber whereby to refrigerate articles supported on the shelf, said shelf being provided with ports, and a baffle mounted upon one edge thereof, overhanging a portion of 115 said ports and serving to deflect air rising through said ports, across said shelf.

5. In a display refrigerator, a refrigerating compartment, a food chamber having a display panel and a shelf, means to effect a 120 circulation of cooling air in said chamber whereby to refrigerate articles supported on the shelf, said shelf being formed with a ribbed top surface, the ribs extending substantially to an edge of the shelf and an upwardly extending baffle mounted on said edge and overhanging a portion of the shelf, thereby 125 to deflect the air over said shelf as it leaves the refrigerating compartment.

6. In a display refrigerator, a food cham-

ber having a display panel and a shelf in said chamber, means to effect a circulation of cooling air in said chamber, both below and above the shelf, means to permit passage of 5 said circulating air upwardly through said shelf, and means on said shelf to direct the air currents in a predetermined course.

7. In a display refrigerator, a food chamber having a display panel and a shelf in said 10 chamber, means to effect a circulation of cooling air in said chamber, both below and above the shelf, means permitting circulation of the air currents from a point below the shelf to a point above the shelf upwardly, and 15 means on said shelf to change the direction of the air currents thereby to direct same over said shelf.

8. In a display refrigerator, a food chamber having a display panel and a shelf in said 20 chamber, means to effect a circulation of cooling air in said chamber, both below and above the shelf, means permitting passage of air past said shelf at a point adjacent said panel, and means on said shelf to deflect 25 the air currents away from the panel.

9. In a display refrigerator, a food chamber having a display panel and a shelf in said chamber, means to effect a circulation of cooling air in said chamber, both below and above the shelf, means permitting circulation of the air currents through the shelf at a point adjacent said panel, and means on said shelf to deflect the air currents away from the panel.

35 10. In a display refrigerator, a food chamber having a display panel and a shelf in said chamber, means to effect a circulation of cooling air in said chamber both above and below the shelf, comprising a refrigerating 40 compartment at one end of the shelf and communicating with the spaces below and above the shelf and a baffle between said compartment and the shelf effective to guide thermo-siphonic currents of air within the refrigerator, said shelf having an opening to permit passage of said circulating air upwardly through the shelf and a baffle on the end of the shelf furthest from said compartment to direct the air currents in a predetermined 50 course.

11. In a display refrigerator, a food chamber having a display panel and a shelf in said chamber, means to effect a circulation of cooling air in said chamber both above and below the shelf, comprising a refrigerating compartment at one end of the shelf and communicating with the spaces below and above the shelf and a baffle between said compartment and the shelf effective to guide thermo-siphonic currents of air within the refrigerator, said shelf having an opening to permit circulation of air from a point therebelow to a point thereabove, and a deflecting baffle spaced from said compartment to change the 65 direction of the air currents over a prede-

termined course thereby to direct same over said shelf.

12. In a display refrigerator, a food chamber having a display panel and a shelf in said chamber, means to effect a circulation of cooling air in said chamber both above and below the shelf comprising a refrigerating compartment at one end of the shelf and communicating with the spaces below and above the shelf and a baffle between said compartment and the shelf effective to guide thermo-siphonic currents of air within the refrigerator, said shelf having a baffle thereon located adjacent said panel to deflect said currents rising toward said panel away from the panel. 70 75 80

13. In a display refrigerator, a refrigerating compartment, a food chamber having a display panel and a shelf in said chamber, means to effect a circulation of cooling air to said chamber both above and below the shelf, comprising a refrigerating compartment at one end of the shelf and communicating with the spaces below and above the shelf and a baffle between said compartment and the shelf effective to guide thermo-siphonic currents of air within the refrigerator, said shelf having an opening to permit circulation of the air currents through the shelf from the refrigerating compartment, and a baffle thereon located adjacent said panel to deflect 90 95 said currents away from the panel. 95

14. In a display refrigerator, a refrigerating compartment, a food chamber having a display panel and a shelf in said chamber, means to effect a circulation of cooling air in 100 said chamber both below and above the shelf, means to support articles on said shelf in spaced relation to the normal top surface of the shelf, means to permit passage of said circulating air from said compartment through said shelf, and means on said shelf to direct the air currents in a predetermined 105 course.

15. In a display refrigerator, a refrigerating compartment, a food chamber having a display panel and a shelf in said chamber, means to effect a circulation of cooling air in said chamber, both below and above the shelf, means to support articles on said shelf in spaced relation to the normal top surface 110 of the shelf, means permitting circulation of the air currents from a point below the shelf to a point above the shelf, and means on said shelf to change the direction of the air currents from said compartment thereby to 115 direct same over said shelf.

16. In a display refrigerator, a refrigerating compartment, a food chamber having a display panel and a shelf in said chamber, means to effect a circulation of cooling air in 120 said chamber, both below and above the shelf, means to support articles on said shelf in spaced relation to the normal top surface of the shelf, means permitting passage of air past said shelf at a point adjacent said panel, 125 130

and means on said shelf to deflect the air currents from said compartment away from the panel:

17. In a display refrigerator, a refrigerating compartment, a food chamber having a display panel and a shelf in said chamber, means to effect a circulation of cooling air in said chamber, both below and above the shelf, means to support articles on said shelf in spaced relation to the normal top surface of the shelf, means permitting circulation of the air currents from said compartment through the shelf at a point adjacent said panel, and means on said shelf to deflect the air currents away from the panel.

18. In a display refrigerator, a refrigerating compartment, a food chamber having a display panel and a shelf in said chamber, means to effect a circulation of cooling air in said chamber, and means including said shelf to define a path for the circulating air through the case, away from the display panel and around articles supported on the shelf, and means to permit passage of said air from said compartment through the shelf.

19. A refrigerator shelf formed with a foraminous surface and a deflecting baffle located at the edge of said surface, said baffle having a portion extending upwardly, inwardly and in overhanging relation to said foraminous surface, and serving to deflect air rising past said shelf, across the same.

20. A refrigerator having a food compartment and a shelf therein for support of foods, said shelf being formed with a foraminous surface and a deflecting baffle located at an edge thereof and having a portion extending upwardly and inwardly and in overhanging relation to said foraminous surface, and serving to deflect air rising past said shelf, across the same and means to effect a circulation of cooling air in said compartment adjacent said shelf.

In testimony whereof I have signed my name to this specification.

REUBEN E. OTTENHEIMER.
